UNITED STATES PATENT OFFICE.

GEORGE C. BLICKENSDERFER, OF STAMFORD, CONNECTICUT; WILLIAM J. BLICKENSDERFER AND STEPHEN S. MAPES EXECUTORS OF SAID GEORGE C. BLICKENSDERFER, DECEASED.

ATTACHMENT FOR AUTOMATIC GUNS.

1,290,828.

Specification of Letters Patent.

Patented Jan. 7, 1919.

Application filed March 6, 1917. Serial No. 152,556.

To all whom it may concern:

Be it known that I, GEORGE C. BLICKENSDERFER, a citizen of the United States, residing at Stamford, county of Fairfield, and State of Connecticut, have invented certain new and useful Improvements in Attachments for Automatic Guns, fully described and represented in the following specification and the accompanying drawings, forming a part of the same.

This invention relates to belt cutting attachments for automatic guns.

In an automatic gun of the belt feed type, cartridges are carried in pockets in a long belt of canvas or similar material. It has been the usual practice to allow the emptied portion of the belt, as it progresses through the gun during the firing operation, to coil or fold up in a box or the like. In the use of such guns in certain circumstances, however, the emptied portion of the belt and any receiving box become inconvenient. For example, when such a gun is used in aeroplanes, the emptied portion of the belt if running free, becomes troublesome and the use of a receiving box is undesirable because of the added weight and space involved.

It is the object of the present invention to do away with these and similar objections and to get rid of the emptied portion of the belt by cutting off the same as it emerges from the gun.

The following specification describes and the accompanying drawing illustrates a belt cutting attachment for automatic guns constructed in accordance with the present invention, it being understood that changes may be made in the form, construction and arrangement of the parts without departing from the invention, the form herein described being a preferred embodiment thereof.

In the drawing—

Figure 1 is a side elevation, with parts in section, of a portion of an automatic gun of the belt feed type having associated therewith a belt cutting device constructed in accordance with the present invention;

Fig. 2 is a top plan view of the same, and

Fig. 3 is a cross-sectional view (enlarged), the section being taken on the broken line 3—3, Fig. 1.

Although the invention is applicable to

any gun of the belt feed type, the gun chosen for illustration and description, is a well-known form of automatic gun in which the parts are operated by a reciprocating cocking lever.

Referring to the drawing, 10 represents the barrel of an automatic gun of the type and form mentioned, having near the muzzle a small vent 11, opening downward from the bore into a gas cylinder 12. Fitting in the latter is a piston 13 pivotally secured to the end of a cocking lever 14. This cocking lever is pivoted to the gun, as at 15, so as to reciprocate as the gun is operated. When a cartridge is fired and before the bullet leaves the muzzle, the pressure of the expanding powder gases against the piston 13 throws the cocking lever back through a considerable arc to substantially the position shown in broken lines in Fig. 1. The cocking lever after having been thrown back by the expanded gases, is returned to its former position by any desirable means, such, for example, as those shown in co-pending application, Serial No. 123,826. Cartridges 16 are held in the loops or pockets of a belt 17 and are positioned for firing by a scalloped star-wheel 18, as appears in Fig. 3. The reciprocation of the cocking lever, as above described, causes the belt to be fed forward step by step and prepares the gun for each successive discharge in a manner well-known in the art, and which it is unnecessary to describe here. As the gun is operated the emptied belt passes out through a belt exit 19 formed in the side of the gun, as more clearly appears in Fig. 3.

The invention includes a cutting device arranged to be operated by the gun to cut off the emptied portion of the belt, and in structures embodying the invention to the best advantage, when the gun in question comprises a part arranged to move during the recoil and return of the gun, the cutting device is arranged to be operated by such moving part, as, for example, the cocking lever forming a part of the gun herein illustrated. Although capable of various constructions, in the present embodiment, secured to the side of the gun is an attachment plate 20 cut away, as shown, to form an opening 21 corresponding to the belt exit of the gun, and through which the emptied portion of the belt passes. Sliding between

this plate 20 and guides 22, secured to the former, is a knife member 23 having a blade 24. This knife is situated to move transversely of the belt exit and is pivotally hung on parallel arms 25, 26, which are in turn pivoted to the plate 20. To operate the knife it is pivotally connected to a link 27 which is, in turn, pivotally connected to a slotted link 28. This latter member is pivoted to the gun, as at 29, and its slot 30 rides over a pin 31 carried by the cocking lever. When the gun is operated the backward swing of the cocking lever, through the slot and pin action just described, swings back 15 the link 28 to the broken line position of Fig. 1. This in turn displaces the link 27 to cause the knife to make its cutting stroke, and due to the construction described the knife is given an oblique parallel motion 20 from the full to the dotted line position of Fig. 1, so as to sever the belt with a "drawing" cut. The return of the cocking lever to its normal position, in a similar manner returns the other parts to their original position. Thus, the operation of the gun, through the reciprocation of the cocking lever, reciprocates the knife and causes it to 25 move transversely of the belt exit to cut off, for each discharge of the gun, a portion of the emptied belt equal to the amount fed.

Fig. 3 shows the end of the emptied belt in a position to have another section cut off,

and it is noted that there is substantially no part of the belt extending beyond the gun itself. It is noted, further, that the cutting device is readily available both for new guns and for those already in use, as it is only necessary to attach the plate 20, the pivot 29 and the pin 31.

What is claimed is:

1. The combination with a belt-feed automatic gun, of a cutting device arranged to be operated by the gun to cut off the emptied portion of the belt.
2. The combination with an automatic belt-feed gun having a part arranged to move during the recoil and return of the gun, of a cutting device arranged to be operated by said moving part to cut off the emptied portion of the belt.
3. The combination, with a belt feed automatic gun having an operating lever operating during recoil, of a cutting mechanism connected to said operating lever and arranged to cut off the emptied portion of the belt.
4. The combination, with a belt feed automatic gun, of a cutting blade arranged to move transversely of the belt exit to sever the emptied portion of the belt, and means for operating said blade.

In testimony whereof, I have hereunto set my hand.

GEORGE C. BLICKENSDERFER.
